UNITED STATES PATENT OFFICE.

HENRY J. ANDERSON AND HENRY VAN WIE, OF SAN FRANCISCO, CALIFORNIA.

MOTOR-CYCLE SUPPORT.

1,215,606.

Specification of Letters Patent. Patented Feb. 13, 1917.

Application filed November 1, 1916. Serial No. 128,911.

To all whom it may concern:

Be it known that we, HENRY J. ANDERSON and HENRY VAN WIE, citizens of the United States, residing at San Francisco, in the county of San Francisco and State of California, have invented new and useful Improvements in Motor-Cycle Supports, of which the following is a specification.

The means usually provided for holding upright a motor-cycle when at rest comprises a yoke-shaped support, the ends of which are pivoted to the rear end of the motor-cycle frame just below the bearings for the rear wheel axle, and the middle, when out of use, is supported by a spring catch depending from the rear end of the rear wheel mud guard. When it is desired to use this support it is released from the spring catch and dropped to the ground, with which it contacts to the rear of the vertical transverse plane through the rear wheel axle, and then the motor-cyclist must raise the rear end of the motor-cycle from off the ground, and move the motor-cycle backward until said vertical plane is behind the part of the ground with which the support is in contact.

Since the latest types of modern motor-cycles are heavy, the lifting of the rear portion of the motor-cycle is quite a laborious task. Moreover, in so lifting the motor-cyclist is almost certain to soil his hands and clothes with the mud and dust on the rear wheel and rear portion of the motor-cycle frame.

The object of the present invention is to provide a simple attachment, which can be readily secured to either side of the aforesaid yoke, and by means of which the rider can employ the weight of his body, transmitted through one foot, to raise the rear part of the motor-cycle from off the ground, and to move the motor-cycle backward so that the point of support of the yoke is in front of the rear wheel axle.

In the accompanying drawing, Figure 1 is a side elevation of the rear portion of a motor-cycle equipped with our invention; Fig. 2 is a perspective view of the attachment detached.

Referring to the drawing, 1 indicates the rear wheel of a motor-cycle and 2 a yoke-shaped support, the ends of which are pivoted to plates 3, (only one here shown) which form part of the frame of the motor-cycle, and through which extends the rear axle of the motor-cycle, said yoke being supported,

when not in use, by a spring catch 4, the upper end of which is secured to a rear mud-guard 5, said spring catch depending from said mud-guard.

Our invention consists of an attachment 6 adapted to be attached to any of the ordinary forms of yoke-shaped support. This attachment comprises front and rear metal bands 7, 8, adapted to surround one side member of the yoke-shaped support, the ends of the metal band 7 extending directly outward from said side member, and those of the metal band 8 extending outward and forward. The outwardly extending ends of the metal band 7 are curved to fit snugly around the lower end of a round arm 9 and are secured thereto by a bolt 10. Between the ends of the rear band 8 is bolted thereto, as shown at 11, the lower end of an oblique brace 12, the upper end of which is secured by a bolt 13 between the rearwardly extending ends of a band 14 surrounding an upper part of the arm 9. Said bands 7 and 8 are secured to the side member of the yoke, and the band 14 is secured to the arm by screws 15, 16 and 17 respectively. The upper end of the arm 9 is bifurcated, and therein is riveted the front end of a pedal 18 extending outwardly and rearwardly.

The following is the mode of use of the device: When the yoke-shaped support has been dropped to the ground in the usual manner, the arm 9 then extends rearwardly and the pedal 18 extends rearwardly and slightly upward. The motor-cyclist then places a foot upon the pedal and rests his weight thereon. The arm 9 and yoke-shaped support 2 then constitute a lever, of which the fulcrum is the outer end of the yoke-shaped support resting upon the ground, its position being then indicated by the left-hand outline in dotted lines in Fig. 1. The rider's weight, then pressing upon said pedal at the rear end of said lever raises the front end of said lever which is attached to the rear end of the motor-cycle frame, so that said front end rotates about said fulcrum as a center, until said rotary motion is arrested by bent portions 19 of the sides of the yoke-shaped support abutting against stops 20 provided on the motor-cycle frame, in which position the transverse vertical plane through the rear axle is behind the point of contact of the yoke-shaped support with the ground, that is to say, the motor-cycle has been moved to the desired position of rest.

While it adds greatly to the utility of our device that it can be attached to the yoke-shaped support of motor-cycles now in use, we also claim to be within the scope of our 5 invention a construction in which the arm 9 is formed integral with the yoke-shaped support.

We claim:—

1. In combination with a support for a 10 motor-cycle at rest, pivoted to the motor- cycle frame at a point adjacent to the rear wheel axle, an arm extending from a side of the support upwardly and of such length and direction that, when the outer end of 15 said support rests upon the ground, the outer end of said arm will be to the rear of the outer end of the support.

2. In combination with a support for a 20 motor-cycle at rest, pivoted to the motor- cycle frame at a point adjacent to the rear wheel axle, an arm extending from a side of the support upwardly and of such length and direction that, when the outer end of 25 said support rests upon the ground, the outer end of said arm will be to the rear of the outer end of the support.

outer end of said arm will be to the rear of 25 the outer end of the support, and a pedal on the outer end of said arm.

3. In combination with a support for a 30 motor-cycle at rest, pivoted to the motor- cycle frame at a point adjacent to the rear wheel axle, an arm rigidly connected to a side of the support and extending upwardly and of such length and direction that, when the outer end of said support rests upon the 35 ground, the outer end of said arm will be to the rear of the outer end of the support.

4. In combination with a support for a 40 motor-cycle at rest, pivoted to the motor- cycle frame at a point adjacent to the rear wheel axle, an arm detachably connected to 45 a side of the support and extending upwardly and of such length and direction that, when the outer end of said support rests upon the ground, the outer end of said arm will be to the rear of the outer end of the support.

HENRY J. ANDERSON.

HENRY VAN WIE.
